(57) **CLAIM**

The ornamental design for a magazine insertion funnel, as shown and described.

DESCRIPTION

FIG. 1 is a front, right, and top perspective view of the magazine insertion funnel showing the new design; FIG. 2 is a front, left, and bottom perspective view thereof; FIG. 3 is a front elevation view thereof, the rear elevation view being a mirrored image thereof; FIG. 4 is a left side elevation view thereof; FIG. 5 is a right side elevation view thereof; FIG. 6 is a top plan view thereof; FIG. 7 is a bottom plan view thereof; FIG. 8 is a section along lines 8-8 of FIG. 3; and, FIG. 9 is a section along lines 9-9 of FIG. 4. The broken lines are shown for the purpose of illustrating unclaimed portions of the magazine insertion funnel and form no part of the claimed design.

1 Claim, 6 Drawing Sheets
